CLAIM

The ornamental design for a handheld weighing scale, as shown and described.

DESCRIPTION

FIG. 1 is a top rear perspective view of a first embodiment of a handheld weighing scale of our design;

FIG. 2 top front perspective view of the handheld weighing scale;

FIG. 3 is a rear elevation view of the handheld weighing scale;

FIG. 4 is a right side elevation view of the handheld weighing scale;

FIG. 5 is a top view of the handheld weighing scale;

FIG. 6 is a front elevation view of the handheld weighing scale; and,

FIG. 7 is a left side elevation view of the handheld weighing scale.

The dash-dash-dash broken line showing is included for the purpose of illustrating portions of the article that form no part of the claim. The dash-dot-dash broken lines are included to depict boundaries of the claim and form no part thereof.

In other embodiments, other portions or other combinations of portions of the handheld weighing scale are shown in solid lines with the remainder of the handheld weighing scale being shown in broken lines.

1 Claim, 7 Drawing Sheets
